KNOTTER

Roberts Tatlock, Gastonia, N. C., assignor to Mill Devices Company, Inc., a corporation of North Carolina

Application December 10, 1932, Serial No. 646,725

24 Claims. (Cl. 289—3)

My invention relates to improvements in knotters for mechanically tying knots in threads, and method of forming a sheet-bend or weaver's knot.

Prior to my invention there have been used and proposed for use several different types of knotters, each designed to form a certain type of knot connecting the ends of threads. Among these various types is the one disclosed in Patent No. 1,572,181 granted to B. E. Byrd, and several features of which are generally desirable. Such features include the means for positioning the two threads to be connected quickly and without difficulty, and the operation of the thread tensioning means and tying bill by a single operating lever. In general, my present invention provides a knitter of the type disclosed in said patent to the extent that it utilizes the general character of thread positioning means, and the operation of the tensioning means and tying bill by a single operating lever. My present invention also provides for operation of thread cutters and a stripping device to remove the knot from the bill by movement of the single operating lever. My present knitter differs from that of the said patent in features of construction and operation hereinafter pointed out in detail.

The general object of my present invention, as to structure, is to provide a compact, sturdy, and easily operated knitter, especially designed to quickly and surely form a sheet-bend or true weaver's knot connecting two threads, and as to method, to so manipulate two substantially parallel threads as to form a knot of the above kind.

In accordance with my invention the two threads are positioned in spaced substantially parallel relation in a plane at substantially right angles to the axis of rotation of the tying bill, but crossing each other in spaced relation at a point in a plane substantially parallel to said axis. I will call the threads so positioned A and B for the purpose of explanation. After the threads have been so positioned they are moved at opposite sides of the bill to reversed positions so as to bring the ends of the thread A down and the ends of the thread B up, thus bringing them into contact between said ends at said point of crossing and forming loops at opposite sides of the point of contact. This is accomplished by the construction and arrangement of the positioning means and subsequent movements of the tensioning and crossing means. The tying bill then successively passes between the threads at opposite sides of the point of crossing. For purposes of further explanation, I will call the portions of

thread A at opposite sides of the point of crossing—*a'* and *a''* respectively. The point of crossing of threads A and B and adjacent parts of the threads are now on one side of the tying bill forming thereon an X, the lower arms of which are formed by *a'* and *a''* and the upper arms by B. The portion *a'* is then looped around the tying bill and across the upper arms of the X and gripped by the tying bill and severed just before the second portion *a''* is disposed behind the tying bill and below the loop in *a'*, after which the stripper pulls on *a''* to move the loop in *a'* across the point of crossing of A and B and the portion of *a'* disposed over the upper arms. As this is happening the upper arm of the X, part of B, is severed, and the stripper then removes and tightens the knot with B around *a''* and loop in *a'* around the both arms of B.

As will be hereinafter more particularly pointed out during the course of the description of the construction and operation of the several parts of the knitter, the knot formed in the foregoing manner is a sheet-bend or true weaver's knot, and the important features of my invention contributing to the formation of the said knot are the relative initial positioning of the threads, subsequent crossing, and movement of the tying bill which is delayed so far as effective engagement with the threads is concerned until the threads have been properly crossed and tensioned.

To the accomplishment of the foregoing and such other objects as may hereinafter appear, my invention consists in the elements and their relation one to the other, as hereafter particularly described and defined in the claims, reference being had to the accompanying drawings which show a preferred embodiment of my invention, and in which

Fig. 1 is a perspective view of a knitter embodying my invention;

Fig. 2 is a view taken on the line 2—2 of Fig. 5;

Fig. 3 is a view taken on the line 3—3 of Fig. 5;

Fig. 4 is a view taken on the line 4—4 of Fig. 5;

Fig. 5 is a view taken on the line 5—5 of Fig. 2 and looking in the direction of the arrows;

Fig. 6 is a perspective view of the operating lever detached from the knitter;

Fig. 7 is a front elevation of the knitter shown in Fig. 1 with the cover plates removed;

Fig. 8 is an enlarged detail fragmentary perspective view showing the initial position of the threads to be connected by the knitter;

Figs. 9—12 are detailed views showing the relative positions of the threads and tying bill during the several steps in forming the knot;

Fig. 13 is a detail view showing the final relative position of the threads in the resulting weaver's knot before tightening.

Fig. 14 is a view similar to Fig. 3 showing a 5 modification in the construction and arrangement of the stripper;

Fig. 15 is a fragmentary rear elevation of the parts shown in Fig. 14; and

Fig. 16 is a view similar to Fig. 14 showing 10 the stripper in its outermost position.

Referring in detail to the drawings, the numerals 1 and 2 designate the side plates of the knotter between which are housed all of the parts except the handle 3 and thumb piece 4 of the 15 operating lever which must conveniently project out. The sides 1 and 2 are held in spaced relation by a plate 5 mounted therebetween with screws 6 engaging through the sides into the plate, there being two screws 6 at each side of the knotter and 20 each end of the plate (Fig. 5). There is also provided, adjacent the point where the handle is joined to the knotter, a base plate 7 which has tongues 8 at each side, seated in openings in the sides 1 and 2. The plate 7 also has portions bent 25 up against the interior of the sides and having openings registering with openings in the sides 1 and 2 to receive screws 9. A curved plate 10 closes the space between the sides 1 and 2 at the front of the knotter and has its forward end bent 30 as at 11 to engage around the pin 12 rigidly connected to one of the sides. The other end of the plate 10 overlaps the plate 7 and a screw 13 is threaded through registering openings in the plate 10 and plate 7 to secure the plate 10 in place. 35 The space between the sides 1 and 2 at the outer end of the knotter may be closed by plate 14 which is flanged along its sides to fit over the beaks 15, which are formed on the outer ends of the sides 1 and 2. The structure thus far described, with 40 the exception of the plate 5, constitutes the casing of the knotter.

Just behind the beaks 15, each of the side plates is provided with a prong, that on the plate 2 being designated by the numeral 16 and that on 45 the plate 1 by the numeral 17. These prongs project upwardly and on each side of each of the prongs there are formed thread receiving notches. The outer notch 18 on the plate 1 terminates above the inner notch 19, or, in other words, the 50 notch 19 is deeper than the notch 18. This is clearly shown in Fig. 1. Referring to Fig. 8, where the prongs and beaks are shown in dot and dash lines, it will be noted that the outer notch 20 in the plate 2, which is in alinement with the outer notch 18 in the plate 1 terminates below 55 the inner notch 21 which is in alinement with the inner notch 19 in the plate 1. Still referring to Fig. 8, it will be noted that the notches 20 and 18 receive one thread and the notches 19 and 21 receive another thread. Now, due to the fact that the notches 20 and 19 terminate below the notches 18 and 21, the threads when placed across the knotter and in the said notches will be located in 60 substantially parallel planes coinciding with the planes through the notches but will cross each other in spaced relation at a point in a plane transversely to the planes of the notches. To facilitate positioning of the threads in spaced relation across the knotter in the proper notches, I may provide an auxiliary divider 22 (Figs. 1, 65 4-7) which comprises a tubular leg 23 to fit over the prong 17 and at right angles thereto at its top an arm 24 extending toward the prong 16. 70 This device may be removably held on the prongs

17 by frictional or resilient grip when applied over the prong.

The first step in the formation of the knot in accordance with my invention is to bring the spaced threads positioned as shown in Fig. 8 into contact and crossed relation as shown in Fig. 9, and to this end I provide at each side of the knotter, preferably on the interior of the casing or adjacent the inner faces of sides 1 and 2, members to engage each of the threads adjacent 5 the notches and move them past each other in reverse directions. In Fig. 3, I have shown the thread crossing means on plate 2 comprising a rocker 25 pivotally connected to the plate 2 at 26, and having a shoulder 27 normally facing the 10 notch 20. A link 28 is pivotally connected to the rocker 25 at 29 and has an offset arm or extension 30 terminating substantially in alinement with the prong 16. This extension 30 on the link 15 is provided with a notch 31 normally in alinement 20 with the notch 21. Obviously, upward or outward movement of the link 28 will rotate the rocker 25 on pivot 26 in a clockwise direction, to carry the shoulder past the notch 20 and thereby move the thread in said notch downwardly or 25 inwardly, while at the same time the upward or outward movement of the link 28 will carry the notch 31 and the thread therein upwardly or outwardly. As the threads are thus moved by the 30 elements 27 and 31, and with respect to the position of the knotter in Fig. 3, the thread which was initially in notch 20 is moved beneath and across the thread which is in notch 31 which is simultaneously moved over and above the first 35 thread.

Now, referring to Fig. 4, there is shown the thread crossing and tensioning means, which is connected to plate 1 and comprising a link 32 pivotally connected at 33 to a rocker 34, which is pivotally connected at 35 to the plate 1. Adjacent 40 the notch 19, the rocker 32 is provided with a lip 36 and immediately therebehind a notch 37, while the rocker 34, which is similar to the rocker 25, has a shoulder 38 in alinement with the notch 18. As in the case of the link 28 and rocker 25, 45 upward or outward movement of the link 32 will cause the rocker 34 to rotate on its pivot 35, but in a contra-clockwise direction, while the lip 36 moves past the notches 19 and 18. During such movement, the rocker 34 carries the outermost 50 thread above and over the innermost thread, while the lip 36 carries the innermost thread below and under the outermost thread, which is just the reverse of the relative movements of the threads under the action of the rocker 25 and link 28. Thus the threads are placed in the position shown in Fig. 9, and the tying bill is ready to come into effective engagement with the threads so positioned and tensioned to form in connection with other parts, hereinafter described, the knot shown in Fig. 13.

The tying bill is of known form and includes the outer clamping jaws 39 between which is the movable jaw 40, pivotally connected by the pin 41, to the jaws 39. The jaw 40 has a flared skirt or cam portion 42 which rotates in the recess 43 in the plate 5, the said recess being arranged eccentrically to the axis of rotation of the tying bill, whereby the cam portion 42 will actuate the jaw 40 at the proper times to open and close. The legs of the jaws 39 extend through an opening 44 in the plate 5, and more particularly in the bottom of the recess 43, and are connected to a shaft 45 for rotation therewith. The lower or inner end 70 75

of the shaft 45 is formed with or keyed to a pinion 46 and is journaled on the end 47 of a screw 48 which is mounted through the plate 7 and rigidly secured in place by a nut 49.

5 The thread crossing and tensioning means and the tying bill, that is, the links 28, 32, and shaft 45, are operated by a common actuating member which might be called a split trigger lever connected to the thumb piece 4. A bolt 50 is mounted through the sides 1 and 2 adjacent the handle 3 and held in place by a nut 51. Between the sides 1 and 2 and on the bolt 50 is journaled the split trigger lever designated generally, (Fig. 2), by the numeral 52. The split trigger lever 52 is illustrated as being composed of two parts one at each side of the knotter adjacent the inner faces of the sides 1 and 2 including generally similar radial parts 53 and 54, the part 53 having a tubular projection 55, and the part 54 having a similar projection 55'. The ends of the projections 55 and 55' have mating tongues and notches forming a clutch-like joint 55'' so that the parts 53, 54, 55 and 55' form practically a unitary split trigger lever journaled on bolt 50. 10 A coil spring 56 surrounds the portion 55' and is anchored at one end to a fixed part, such as the plate 7 and at its other end to the portion 54, as shown in Fig. 3. The spring normally tends to maintain the parts in the position shown in Figs. 20 2 and 3 with the thumb lever 4 up and pins 57 on the links 28 and 32 disposed in the ends of notches 58 in the respective portions 53 and 54. The pins 57 and the notches 58 are in alignment across the knotter. Each of the portions 53 and 35 54 has on its upper face at one side of the notches 58, arcuate surfaces 59, and on the other side of the notches projections 60 extending beyond the top of the surfaces 59. Furthermore, each of the sides 1 and 2 has a pin 61 disposed in slots 40 62 formed longitudinally in the links 28 and 32.

Describing the operation of the split trigger lever with respect to the thread crossing and tensioning parts, when the thumb piece 4 is pulled down or to the left of the position shown 45 in Fig. 2, the pins 57 are moved in an arc and being in the notches 58, cause the links 28 and 32 to be simultaneously and equally moved upwardly or outwardly thus moving the notch 31 and lip 36 and rotating the rockers 25 and 34 to cross the threads in the manner hereinabove described.

The ultimate position of the threads under movements of the crossing and tensioning means is established just as the pins 57 reach the ends of the slots 58, and continued movement of the thumb piece 4, and consequent rotation of the split trigger lever, brings the arcuate faces 59 across and below the pins 57, so that the threads are maintained in the crossed relation under proper tension. The movement of the links 28 50 and 32 is limited by the travel of the lugs 61 in the slots 62.

Referring to Figs. 2 and 7, it will be noted that a toothed segment 63 is pivotally mounted on the bolt 64 which extends through the side 1, being held in place by the nut 65. This segment is provided with a cam slot or groove 66 in which is disposed a lug 67 mounted at the end of an extension 68 on the plate 53. The first movement of the thumb piece 4 and rotation of the split trigger lever moves the pin 67 in the shorter end portion 66' of the groove 66, so that during such movement, which is equivalent to the initial crossing movement of the parts 25, 28, 32, 34, the segment is not moved. However, when the pin 70 75 67 reaches the curve 69 of the cam slot 66, it con-

tacts the wall at the curve and begins to move the segment, which movement is continued as the pin moves along the longer or intermediate portion of the groove 66. Now, since the teeth of the segment 63 mesh with the pinion 46, the partial rotation of the segment which takes place during the travel of the pin 67 along the longer intermediate portion of the groove 66 rotates the shaft 45, and the rotation of the shaft stops as the pin enters and moves in the other end portion 70 10 of the groove 66, at which time the operation of parts hereinafter described is taking place.

In the present embodiment of the invention, I have shown the tying bill jaws facing rearwardly of the threads in the normal position of 15 the parts, which position is that occupied by the several parts before the thumb lever 4 is moved. The length of the end 66' of the cam groove 66 is such as to delay rotation of the tying bill until such time as the threads have been brought into 20 contact and crossed, or, in other words, such that the effective engagement of the tying bill with respect to the threads is delayed until the proper crossing of the threads is accomplished. So far as I am aware, in the knotters heretofore used or 25 proposed, the tying bill faces to the front and the threads are positioned across its jaws, so that the tying bill usually comes into effective engagement with the threads substantially simultaneously with their crossing. In other respects, the 30 mechanical operation of the tying bill so far as the clamping and cutting jaws is concerned is the same as in Patent No. 1,572,181. With the type of knot tied with my knotter and under my method, it is necessary to also pick up and sever another 35 thread. To this end, I provide between the beaks 15, a plate 72, the ends of which are flanged and secured to the beaks 15 by screws 73. Another plate 74 is secured to the plate 72 by screws 75 and has a depending side 76 formed with a cutting edge 77. A movable blade 78 is pivotally connected at 79 to the plate 76 and has a cutting edge 80. The cutting blade 78 is provided with a pin 81 disposed in a slot 82 in the end of a lever 83, which is pivotally mounted on a pin 84 45 which extends across a groove in the plate 5. A coil spring 85 is mounted around the pivot 84 and has one end anchored against the plate 5 and the other end anchored against the lever 83 to normally hold the parts in the position shown in 50 Fig. 2. However, when the thumb piece 4 has been pressed down so as to rotate the split trigger lever and thus cross the threads and rotate the tying bill, and more specifically just about at the time that the pin 67 begins to move in 55 the end 70 of the cam groove 66, the extension 60 on the plate 53 moves into contact with the end 86 of the lever 83 and continued final movement of the split trigger lever and cam finger 60 moves the end 86 of the lever 83 so as to rotate 60 the lever on the pivot 54 against the tension of spring 85 to move the slot 82 across the pin 81 and eventually to move the pin and blade 78 sufficiently to cross the cutting edges 80 and 77. During such movement of the blade 80, it has picked up the other thread which is to be severed as 65 hereinafter pointed out.

The final mechanical operation is the stripping or removal of the threads from the tying bill. This is accomplished by a movement imparted 70 to the stripper also by the split trigger lever.

Referring to Figs. 3, 7, the stripper is designated generally by the numeral 90 and is pivoted intermediate its ends on the bolt 91 mounted through the side 2. At its rear, the stripper has 75

an arm 92 normally contacted by an extension 93 on the plate or portion 54 of the split trigger lever. At its other end, the stripper has the usual hook 94, and between the hook 94 and 5 the pivot 91, the stripper is provided with a cam arm 95 disposed in the path of movement of the extension 93 on part 54. The arm 95 is located at a point remote from the normal position of the extension 93 so that it will not be contacted 10 thereby until after the pin 67 has moved into the end 70 of the slot 66, which is after the tying bill has completed its rotation, and also after the finger 60 on part 53 has contacted the end 86 of the lever 83 to move the blade 78 to sever the 15 thread cut thereby. When the extension 93 does engage the arm 95 it partially rotates the stripper 90 on the pivot 91 moving the hook 94 through an arc toward and across the tying bill and slots 20 and 21, so that the hook will catch a particular 20 thread to complete the formation of the knot by tightening the interlocked threads and removing the knot from the tying bill.

I believe that the foregoing description of the 25 respective parts of the knotter and their operation is sufficiently detailed to afford a clear understanding of the construction and operation of the knotter, but if there be any points not clearly understood, the same should become apparent during the course of the following 30 description of the formation of the knot.

Referring to Fig. 8, it will be noted that the two threads to be joined are laid through the notches on opposite sides of the prongs 16 and 17 respectively with the outermost thread, which 35 is shown as being white and designated by the reference A, in the outermost notches 20 and 18 and in front of the shoulders 38 and 27 on the rockers 34 and 25 respectively, and the other thread which is shown striped, and designated by the reference B, is disposed in the aligned inner notches 21 and 19 and hence in the notch 31 of the link 28 and in front of the lip 36 on the link 32. That portion of the thread B which is in the notch 31, is above or higher than the 40 portion of the thread A, which is in the bottom of the notch 20 at one side of the knotter, while the portion of the thread B, which is in front of the lip 36, is lower than the portion of the thread A, which is in the notch 18 at the other 45 side of the knotter, so that when the thumb lever is initially depressed, to cause rotation of the split trigger lever whereupon the link 28 moves outward, the portion of the thread B in the notch 31 will be carried over the portion of the thread 50 A in notch 20 which latter portion is moved under the thread B and inward. At the same time at the other side of the knotter the portion of the thread B which is in front of the lip 36 is moved outward and under the portion of the 55 thread A, which is in the notch 18 which latter portion is moved inward and over the thread B, so that the threads are crossed in the manner shown in Fig. 9 at a single point. As the threads were being so positioned, the tying bill rotated 60 substantially 90° which places it in the position relative to the crossed threads shown in Fig. 9, the threads being crossed substantially in alignment with the axis of the bill. That portion of the thread A between the shoulder 38 and the 65 point of crossing of the threads will hereinafter be referred to as a' while the portion of the same thread between the point of crossing and the shoulder 27 will be referred to as a''. Similarly 70 the portion of the thread B between the lip 36 and point of crossing will be referred to as b'

and the remaining portion between the point of crossing and notch 31 as b''. When the tying bill rotates 180° from the position shown in Fig. 9, which is substantially 270° from its original position, it will be in the position shown in Fig. 10 and has passed between a' and b', and is beginning to pass between a'' and b'' with a' beginning to loop around the tying bill.

The four strands a', a'', b', and b'', adjacent their points of crossing have thus been formed 10 substantially into an X on one face of the tying bill. When the tying bill rotates another 180° from the position shown in Fig. 10, it will be in the position shown in Fig. 11, and a' has been 15 looped around the tying bill to form the loop indicated by L and has crossed over b' and b'', and the cam portion 42 of the tying bill has been actuated to open the jaws 39 and 40, so that a' is placed between the jaws. Continued 20 movement or rotation of the tying bill closes 25 the jaw 39, and when the tying bill has substantially made a complete revolution and a half, from its starting point, or has revolved substantially 540°, the bills are facing forwardly; a' is 30 looped as shown in Fig. 12 around the tying bill 35 and across b' and b''; the cutting blade 78 is catching b' and carrying it toward the edge 77; the stripper is moving up to a'' and the segment 63 has reached its limit of movement because pin 67 is in the portion 70 of the cam slot 66. Continued 40 movement of the split trigger lever pulls a'', causes b' to be severed and pulls the loop L over the bill across the point of crossing of the threads and across the end of a' gripped between the jaws. The resulting knot is shown in Fig. 13 45 in loosened condition.

When the knot has been removed and the thumb piece 4 is released, the spring 56 will 40 rotate the split trigger lever, and as the pin 67 moves out of the end 70 and into the long intermediate portion of the cam slot 66, the segment will be rotated in reverse direction and the parts returned to the position shown in Fig. 2. The spring 85 returns the lever 83 to its 45 normal position when the finger 60 moves out of contact with the end 86 on the return movement of the segment, and of course the return movement of the segment moves the arcuate faces 59 reversely so that the pins 57 will come into the slots 68 and move down therein to return the crossing members to their original position.

It is possible to provide for the stripper remaining in its outermost thread engaging position, after it has engaged the thread to tighten 55 and remove the knot, to hold the knot out of the machine during the return movement of the bill, thread crossing means, and other movable parts. A construction and arrangement for effecting this is shown in Figs. 14-16, wherein 60 the numerals 2, 5, 7, 10, 16, 25, 50 and 55' designate the same parts as in the other figures of the drawings. The plate 54' of Figs. 14-16 is the same as the plate 54 of the other figures and operates in the same manner. However, the arm 65 93' is slightly different than the arm 93 in that it is offset at 100, so that its outer end is nearer to the side plate 2 and in the same plane with the extension 95' on the stripper lever and similar to the arm 95 of the other figures. Instead 70 of providing the rearwardly extending arm 92 of the stripper previously described, I provide at the rear of the pivot 91' for the stripper, a loop 101 in which is disposed the curved end 102 of lever 103. The curved end 102 terminates at a 75

shoulder 104. The other end of the lever 103 is in the same plane with and contacts the end of the arm 93' and may be provided with a curved cam surface 105 for engagement by the 5 end of the arm. The end of the lever 103 or cam surface 105 is normally urged toward the end of the arm 93' by spring 106 secured at 107 to the base plate 7 as by rivets or welding. Instead of providing the stripper with the plain 10 hooked end 94 as of the other figures, the arrangement of Figs. 14-16 shows the arm 94', provided at its end with a curved extension 108 terminating forwardly at a shoulder 109, which is adapted to engage the thread when the stripper 15 is rotated on the pivot 91 by engagement of the arm 93' with the extension 95' as in the other figures. The outermost position of the stripper is shown in Fig. 16, and it will be noted that partial rotation of the stripper has moved the 20 loop 101 along the curved end 102 of the lever 103 and behind the shoulder 104. The spring 106 will maintain the parts in the position shown during the return movement of the arm 93' to the position of Fig. 14, at which time the thread 25 crossing members, rotary tying bill, and lever 83 are returning to normal position. The curved extension 108 is disposed between the thread crossing members and tying bill and will prevent tangling of the threads. When the arm 93' 30 returns to the position of Fig. 14, it engages the surface 105 rocking the lever 103 on its pivot 110 against the action of the spring 106 and releasing the shoulder 104 from engagement with the loop 101, whereby the spring 111, which is 35 anchored at 112, to the frame of the knotter and at 113 to the stripper lever may return the stripper to the position of Fig. 14. Thus, all of the parts except the stripper return to their normal position after the knot is tied except 40 the stripper which remains in thread engaging position until all of said parts have reached their normal positions, so that the tying bill cannot retain the knot and in its reverse rotation sever the same. The structure of Figs. 14-16 is not 45 absolutely essential to operation of the knotter, but I find the same to be very practical and useful.

I claim:

1. A knotter comprising a tying bill, means to 50 rotate said bill, guides to position a pair of threads across the knotter in spaced substantially straight condition and substantially parallel to a common plane, and means for bringing said threads into contacting crossed relation at a single point of 55 crossing located for engagement by the tying bill and for passage of the tying bill between the threads successively on opposite sides of the point of crossing during rotation of said bill.

2. A knotter comprising guides to position a 60 pair of threads in spaced relation, a tying bill, means at each side of the tying bill to reverse the relative positions of the threads at opposite sides of the tying bill while bringing them into crossed contacting relation at a point intermediate said guides, and means to rotate said tying bill after said threads have been crossed in contacting relation to bring a side of the tying bill into contact with the point of crossing and pass its point successively between the threads on opposite sides of the point of crossing.

3. A knotter comprising side plates each 75 provided with a pair of notches and the pairs of notches being alined to receive threads positioned thereby in substantially straight stretches in spaced relation, means adjacent said notches at

each side of the knotter to reverse the position of the threads by passing one over the other at one side and said other over the said one at the other side to cross said threads at a single point intermediate said sides, a tying bill having jaws initially disposed behind said threads and out of contact therewith during the crossing, a shaft connected to said bill, and means to rotate said shaft and tying bill to pass said jaws between said threads at opposite sides of the point of crossing 10 successively after they have been so crossed.

4. The structure of claim 3 wherein the means for rotating said tying bill comprises a pinion connected to the shaft of the tying bill, a rack meshing with said pinion to impart rotary movement 15 thereto and to said shaft and bill, and cam means for moving said rack at a predetermined interval relative to the movement of the thread crossing means.

5. In a knot tying device, in combination, spaced 20 alined guides for receiving and separating two threads in planes substantially parallel to a common plane and crossing one another in spaced relation in another plane, mechanism for moving the said threads in reverse directions at opposite 25 sides of the device to bring the threads into contact at said point of crossing, means for folding said threads across each other at said point of crossing, and then looping one thread about said means, and means for pulling said loop over said 30 point of crossing and against a portion of said one thread.

6. In a knotter, a frame comprising spaced rigidly connected side plates, a tying bill rotatably supported therebetween, means on said side plates 35 for positioning two threads in spaced relation across said sides, means for crossing said threads intermediate said sides, a lever for actuating said thread crossing means, a rack and pinion for rotating said tying bill, a member supporting said 40 rack and pivotally supported by a part of said frame, a cam formation on said member, and an element carried by said lever for engaging said cam formation and movable relative thereto during the operation of the thread crossing means 45 without moving said member, and movable relative thereto after said threads have been crossed to oscillate said plate and rack to rotate said pinion and tying bill.

7. In a knotter, side plates rigidly connected in 50 spaced relation, a tying bill rotatably supported therebetween, means on each of the side plates for guiding two threads into spaced relation between the sides, a link at each side of the knotter and slidably therealong, each of said links having 55 one end terminating adjacent one of the threads, a rocker pivotally connected to each of the links and having a portion disposed adjacent the other thread, said rockers being pivotally connected intermediate said portion and pivotal connection to the sides, a lever pivotally supported between the sides and having two spaced portions one adjacent each of the sides, cam means on each of said portions and links for moving said links outwardly 60 and rotating said rockers upon rotation of said lever to cross the threads intermediate said sides, and means operable by said lever to rotate said tying bill and pass it successively between the threads at opposite sides of said point of crossing. 65

8. The structure of claim 7 wherein the means for rotating the tying bill comprises a shaft connected therewith, a pinion on the shaft, a segment 70 plate pivotally mounted between the sides and carrying an arcuate rack and provided with a cam 75

- slot, said cam slot having an offset and an elongated portion, and a lug on the lever normally resting in said offset portion and movable therein during initial movement of the lever and thread crossing means without moving said segment, and movable in said elongated portion after the threads have been crossed to rotate the rack, pinion, and tying bill.
9. In a knot tying device, in combination, a tying bill having fixed and movable clamping and cutting jaws, means for positioning two threads relative to each other across the tying device in spaced relation and parallel to a common plane, means for reversing the relative positions of the threads at the sides of the knotter while crossing the threads at a point intermediate said sides, means for rotating the tying bill to cause the same to pass between the threads at opposite sides of said point of crossing successively, means to open said jaws to receive one of said threads at one side of said point of crossing after the tying bill has passed successively therebetween, said means being effective to close said jaws to clamp said thread and subsequently sever it, means to catch the other thread above said first thread at the same side of the point of crossing and to subsequently sever it, and means engageable with said first thread at the other side of the point of crossing to strip the knot from the tying bill.
10. In a knotter including means to position a pair of threads in spaced relation thereacross, means to cross the threads at a single point intermediate the sides of the knotter, a tying bill, means to rotate the tying bill, a thread severing device and a stripper, an operating lever pivotally mounted between the sides and having associated therewith a plurality of cam formations to successively operate the said thread crossing means, bill rotating means, thread severing device and stripper.
11. In a knotter having thread positioning and knot forming elements, an actuator for moving said elements comprising a lever, spaced plates on said lever each having a curved edge terminating at one end at a slot, and extensions on said plates at the other end of said curved faces, said plates being located at opposite sides of the knotter.
12. The structure of claim 11 wherein said lever is formed of two parts, each part including one of said plates, and a tubular sleeve projecting therefrom, the ends of said sleeves having mating interfitting elements to form a clutch-like joint between the parts.
13. In a knotter including side plates rigidly connected in spaced relation and each provided with a pair of notches to receive threads and position the threads in spaced relation, a link extending along the inner face of each of the plates and each terminating at one end adjacent aligned opposite notches and having a formation at said point of termination to engage a thread, the formation on one of said links being a turned edge and on the other link a notch to receive one of the threads.
14. In a knotter having thread positioning and knot forming elements including a rotatable tying bill, means to rotate said bill to loop the threads thereon, a stripper to pull the looped threads over the bill, said stripper comprising a lever having means for pivotally mounting it within the knotter, and having a rearwardly extending arm and a forwardly extending arm terminating in a hook to catch a thread, said arms being arranged on opposite sides of the pivot point, a lateral extension on said stripper, and means to engage said rear arm and hold the lever against rotation and to also engage said lateral extension to rotate the lever and move said hook.
15. The structure of claim 14 wherein the means for engaging said rear arm and lateral extension comprises a member carried by the bill rotating means.
16. In a knotter including means to position a pair of threads and a rotatable tying bill to loop the threads, means to rotate said tying bill, and means to catch one of the threads and sever it at a predetermined time, said last means comprising a lever pivotally mounted in the knotter and having an elongated arm formed with a slot adjacent its end, a movable cutting blade, a pin connected to said cutting blade and disposed in said slot, a fixed cutting blade, a pivotal connection between the said fixed cutting blade and movable cutting blade, and means to engage said lever to rotate it past said slot across said pin and then move said movable blade into cutting engagement with the fixed blade.
17. The structure of claim 16 wherein the means for moving said lever comprises a member carried by the bill rotating means and engageable with an end of said lever.
18. In a knotter of the class described, having aligned prongs separating thread receiving notches, an auxiliary thread separator frictionally secured to one of said prongs and having an arm extending partly across said knotter toward the other prong, said auxiliary separator being readily detachable by sliding movement along said prong.
19. In a knotter of the class described, having aligned prongs separating thread receiving notches, an auxiliary thread separator comprising a tubular portion to fit over one of said prongs, and an arm at the upper end of said portion extending partly across the knotter toward the other prong.
20. In a knotter of the class described, means to position and cross a pair of threads, a tying bill, means to rotate said tying bill between the crossed threads to loop said threads thereon, means to tighten said looped threads on the tying bill comprising a stripper engageable with one of the threads, and means to maintain said stripper in thread engaging position during return movement of the tying bill.
21. A knotter comprising a tying bill, means to rotate said bill, guides to position a pair of threads across the knotter in spaced substantially straight condition and substantially parallel to a common plane, and means independent of the tying bill for bringing said threads into contacting crossed relation at a single point of crossing located for engagement by the tying bill and for passage of the tying bill between the threads successively on opposite sides of the point of crossing during rotation of said bill.
22. In a knot tying device, in combination, spaced aligned guides for receiving and separating two threads in planes substantially parallel to a common plane and crossing one another in spaced relation in another plane, mechanism for moving the said threads in reverse directions at opposite sides of the device to bring the threads into contact at said point of crossing substantially in alignment with the axis of the tying bill, means for folding said threads across each other

at said point of crossing, and then looping one thread about said means, and means for pulling said loop over said point of crossing and against a portion of said one thread.

5 23. A knotter comprising side plates rigidly connected in spaced relation, guides at opposite sides of the knotter to position a pair of threads across the knotter in spaced substantially straight condition and substantially parallel to a common plane, means for bringing said threads into contacting crossed relation at a single point of crossing intermediate the sides of the knotter, a tying bill having its beak normally facing away from the thread guides, and means to rotate said tying bill to bring one side thereof into engagement with the threads at their point of crossing and to pass the beak of the bill between the crossed threads successively on opposite sides of the point of crossing.

10

15

24. A knotter comprising side plates rigidly connected in spaced relation, guides at opposite sides of the knotter to position a pair of threads across the knotter in spaced substantially straight condition and substantially parallel to a common plane, means for bringing said threads into contacting crossed relation at a single point of crossing intermediate the sides of the knotter, a tying bill having its beak normally facing away from the thread guides, and means to rotate said tying bill to bring one side thereof into engagement with the threads at their point of crossing and to pass the beak of the bill between the crossed threads successively on opposite sides of the point of crossing, means to strip the knot from the beak, and means to delay the return movement of the stripping means until after the tying bill has returned substantially to its normal position.
